UNITED STATES PATENT OFFICE.

JOSEPH MELLING, OF JACKSON, MICHIGAN.

APPARATUS FOR TURNING IRREGULAR FORMS.

Application filed December 6, 1920. Serial No. 428,567.

To all whom it may concern:

Be it known that I, JOSEPH MELLING, a citizen of the United States, residing at Jackson, county of Jackson, State of Michigan, have invented a certain new and useful Improvement in Apparatus for Turning Irregular Forms, and declare the following to be a full, clear, and exact description of the same, such as will enable others skilled in the art to which it pertains to make and use the same, reference being had to the accompanying drawings, which form a part of this specification.

My invention relates to apparatus for turning irregular forms and a special object of my improvements is to provide an improved apparatus for turning the cams on the valve-actuating shaft of an internal combustion engine.

20 In the accompanying drawings:

Figure 1 is a side elevation of an apparatus embodying my invention.

Fig. 2 is a plan of the same partly broken away.

25 Fig. 3 is a front elevation looking from the left of Fig. 1, parts being broken away as indicated by the broken line III—III Fig. 1 to show the internal construction.

Fig. 4 is a section in the plane indicated 30 by the line IV—IV, Fig. 3.

a is the bed or frame of the apparatus. Rising from the upper portion of the frame a are guide plates b and a standard c. There are a number of pairs of parallel guide plates b as indicated distinctly in Figs. 2 and 3.

Between each pair of guide plates b is a reciprocating carrier d. d² is a spring one end of which engages against the upper end 40 of the standard c and the other end against a carrier d. d² is a hanger integral with and extending downward from the carrier d. e is a friction wheel bearing in the lower end of the hanger d².

45 j is a tool holder pivoted at j² upon a carrier d and extending in front of said carrier.

j³ is a similar tool holder pivoted at j⁴ to the carrier d and similarly extending in front of said carrier. j⁵ j⁶ are the tools held in the 50 holders j and j³. j⁶ is a connecting rod pivoted at j⁷ to the upper tool holder j³ and at j⁸ to the lower tool holder j.

q is a friction wheel on the lower end of the connecting rod j⁶.

55 p indicates a carriage adapted to reciprocate transversely of the base or frame a,

into which it is dovetailed for that purpose, in front of the carriers d. p² is a screw-threaded rod leading screw that may be turned by a handle p³ to move the carriage p in its ways. r and r² indicate lathe heads, or work holders, adapted to support the work in position to be operated upon by the tools j⁵. s and s² indicate cam shafts secured respectively in the holders or supports r and r². The shafts s and s² are shaped to have cams s³ cut and formed thereon by the operation of the apparatus. The tools j⁵ j⁶ are held and adjusted by the apparatus to shape the cams to their proper form.

f is a cam adapted to act upon the friction wheel e, in conjunction with the spring d³, to reciprocate the carrier d. g is a gear wheel on the same shaft as the cam f. h is a gear wheel upon the power-receiving shaft h², its 70 teeth engaging the teeth of the gear wheel g. i is a cam of approximately the shape indicated, its active surface engaging the friction wheel q at the lower end of the connecting rod j⁶.

k is a gear wheel adapted to rotate the shaft s, its teeth engaging the teeth of the gear wheel h. n is a gear wheel adapted to rotate the shaft s². m is an intermediate wheel engaging the teeth of both the wheels 80 k and n.

The operation of the above described device is as follows:

Power is applied to rotate the shaft h² by means of a belt and pulley or otherwise. The 90 motion of the shaft h² is conveyed to the cam f and the shafts s and s² through the gearing above described. The cam f now acts in conjunction with the spring d³ to reciprocate the carrier d. The cam i acts in conjunction 95 with the spring j⁹ to reciprocate the connecting rod j⁶ and thereby to oscillate the tool holders j and j³ about their bearings j² and j⁴. In this way the motions imparted by the cams f and i to the tools j⁵ j⁶ always 100 holds said tools in the proper cutting position and cause them to properly and accurately shape the cams upon the cam shafts.

I have shown the tool holders and apparatus for working upon two shafts s and s² at 105 the same time; of course only one might be operated upon.

I have also shown a plurality of carriers d with their appurtenants for cutting a plurality of cams upon the same shaft.

110 The above construction brings the cam i close to the tool so that there is substantially

no lost motion between the tool and the cam. The force exerted upon the tool is mostly conveyed to the cam without being transmitted to the cam *d* or parts secured thereon.

5 The two tool holders, one arranged above the other, are directly connected so that they move in unison and the connections are strong and rigid so that the positions of the tools are certain under all working conditions.

10 The cam *i* is of a simple form involving no sharp changes of direction, or great rate of acceleration of the actuated parts.

Claims:

15 1. In an apparatus of the kind described, a carrier adapted to be reciprocated, a pair of tool holders supported by said carrier, said holders having a freedom of motion independent of that of the carrier, means connecting said tool holders to constrain the relative movements of the same, a rotary work holder disposed within operable relationship of each tool holder.

20 2. In an apparatus of the kind described, a carrier adapted to be reciprocated, a pair of tool holders supported by said carrier having an oscillating motion independent of that of the carrier and at an angle to the motion of the carrier and a connecting rod pivoted to each tool holder to impart oscillating movement thereto, and a work holder disposed within operable relationship of said tool holders.

25 3. In an apparatus of the kind described, a carrier adapted to be reciprocated, a plurality of tool holders pivoted to said carrier,

a connecting rod pivoted to each of said tool holders, a cam to reciprocate the carrier, a cam to reciprocate the connecting rod to oscillate the tool holders about their pivots in a direction at an angle to the movement of the carrier, and a work holder disposed within proximity of each tool holder to support a piece of work within operable relationship thereof.

40 4. In apparatus of the character described, a spring-constrained carrier, a cam to cooperate with the spring to reciprocate the carrier, a plurality of tool holders pivotally supported by the carrier for oscillating movement angularly the movement of the carrier, cam-controlled means to simultaneously oscillate said tool holders, a rotatable work support for each tool holder disposed to support a piece of work within operable relationship thereof.

45 5. In apparatus of the character described, a movable carrier constrained in a given direction by a spring, a cam to actuate said carrier against the resistance of the spring to cause in co-operation with the spring reciprocation of the carrier, a plurality of tool holders pivotally supported by the carrier, a cam-controlled member to simultaneously oscillate said tool holders angularly the direction of travel of the carrier, a work holder for each tool holder disposed to support a piece of work within operable relationship thereof.

50 In testimony whereof, I sign this specification.

JOSEPH MELLING.
